US0D1090980S

(12) **United States Design Patent** (10) **Patent No.:** **US D1,090,980 S**
(45) **Date of Patent:** **** Aug. 26, 2025**

(54) **AEROSOL GENERATOR**

(71) Applicant: **Nicoventures Trading Limited**,
London (GB)

(72) Inventors: **Jared Aller**, Winston-Salem, NC (US);
Ali Gallaher, London (GB); **Kang Min Kim**, London (GB); **Andy Vernal**, London (GB)

(73) Assignee: **NICOVENTURES TRADING LIMITED**, London (GB)

(**) Term: **15 Years**

(21) Appl. No.: **29/945,034**

(22) Filed: **May 31, 2024**

Related U.S. Application Data

(63) Continuation of application No. 29/837,326, filed on May 4, 2022, now Pat. No. Des. 1,048,540.

CLAIM

The ornamental design for an aerosol generator as shown and described.

DESCRIPTION

FIG. 1 is a top front perspective view of an aerosol generator showing the claimed design;

FIG. 2 is a bottom rear perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof; and,

FIG. 8 is a right view thereof.

(Continued)

The broken lines in the drawings illustrate portions of the aerosol generator that form no part of the claimed design.

1 Claim, 8 Drawing Sheets
